DRILLING MACHINE

Albert Hossfeld, Winona, Minn.

Application June 7, 1940, Serial No. 339,294

8 Claims. (Cl. 255—40)

My present invention relates to improvements in drilling machines of the type disclosed and broadly claimed in my United States Letters Patent No. 1,888,668, issued November 22, 1932.

The object of this invention is to modify certain parts of the drilling machine above referred to and to add certain attachments thereto, whereby samples of the material or materials, through which the bit of the drill is passing, may be taken.

While the invention is intended for general use, it provides a drilling machine especially well adapted for prospecting for coal, for clay for use in making brick, and the like.

To the above end, generally stated, the invention consists of the novel devices, combination of devices and arrangement of parts hereinafter described and defined in the claims.

In the accompanying drawing, which illustrates the invention, like characters indicate like parts throughout the several views.

Referring to the drawing:

Fig. 1 is a fragmentary perspective view of a drilling machine having the invention embodied therein;

Fig. 2 is a fragmentary view partly in side elevation and partly in longitudinal central section of the drill bit, the adaptor, and the shaft, on an enlarged scale;

Fig. 3 is a view partly in side elevation and partly in longitudinal central section showing the parts illustrated in the upper right-hand portion of Fig. 1, on an enlarged scale;

Fig. 4 is a view corresponding to Fig. 3 but showing the parts illustrated in the upper left-hand portion of Fig. 1, on an enlarged scale;

Fig. 5 is a view partly in plan and partly in horizontal section taken on the line 5—5 of Fig. 3;

Fig. 6 is a view partly in end elevation and partly in vertical section taken on the line 6—6 of Fig. 3; and

Fig. 7 is a fragmentary view showing the rope guide and the mast supporting the same, on an enlarged scale.

Of the parts of the drilling machine fragmentarily illustrated, it is important to note the main frame 8, the secondary frame 9 rigidly mounted on the main frame, the tilting frame 10 mounted on said secondary frame, and the reciprocating carriage 11, mounted on the tilting frame 10. The carriage 11 is reciprocated by a pair of upright connecting rods 12 pivotally attached at their upper ends to said carriage. These connecting rods 12 are pivoted at their

lower ends to crank pins 13, one of which is secured to a crank-acting sprocket wheel 14 secured to a horizontal transverse shaft 15 journaled in bearings on the tilting frame 10. The other crank pin is secured to a counterweighted crank arm, not shown, on the shaft 15. For the purpose of this case it is not thought necessary to illustrate the mechanism for driving the sprocket wheel 14, however it may be assumed that an internal combustion engine is mounted on the main frame 8 with transmission mechanism from said engine to the sprocket wheel 14.

The drill proper, which forms part of my present invention, includes a hollow sectional steel shaft 16, only two sections of which are shown, and these sections are separably connected by a short coupling 17, the body of which is identical with the shaft 16. The end portions of the coupling 17 are reduced in diameter, fitted into the respective end portions of the shaft 16 and have screw-threaded engagement therewith. It is, of course, understood that as the drilling operation progresses, other sections will be successively coupled to the shaft 16 in the drilling machine.

An adaptor 18 is rigidly secured to the lower end of the shaft 16 and a bit 19 is detachably secured, by screw-threads, to the lower end of said adaptor. Hereinafter, for the sake of clearness, the shaft 16, the adaptor 18 and the bit 19 will be referred to as the drill.

Referring again to the well known parts of the drilling machine, the drill is mounted on the tilting frame 10 for compound endwise and rotary movements. Part of the mountings for the shaft 16 in the tilting frame 10 includes a main sleeve bearing 20 turnably mounted on the tilting frame 10.

The following connections, actuated by the reciprocating carriage 11, are provided for turning the bearing 20 about its axis to assist in imparting step-by-step movement to the drill, to wit: a crank arm 21, rigidly secured to the bearing 20, is connected by a tilting link 22 to said carriage, as indicated at 23. A friction grip 24 is applied to the shaft 16 and through which grip the shaft 16 is automatically moved to feed the bit 19 to its work. Co-operating with the friction grip 24 is an abutment in the form of a striker plate 25 on the tilting frame 10 below said grip.

The drill is endwise reciprocated by a compression propelling coiled spring 26 and a compression buffer coiled spring 27 under the action of the reciprocating carriage 10. These springs

26 and 27 encircle the shaft 16, the former above the friction grip 24 and the latter below the same. The spring 26 is rigidly secured at its upper end to the main bearing 20 and the spring 27, at its lower end, is secured to the carriage 11. Both springs 26 and 27 at their inner ends are loose and the latter loosely extends through an aperture in the striker plate 25. Normally the friction grip 24 rests on the buffer spring 27 and at this time there is considerable clearance between the said grip and the propelling spring 26.

The drilling operation may be briefly described as follows, to wit: It may be assumed that the carriage 11 is in its lowermost position, with the bit 19 resting on the material to be drilled, that the grip 24 is resting on the striker plate 25, that the propelling spring 26 is expanded to its full length and that the buffer spring 27 is compressed to a point in which its upper end is flush with the striker plate 25. From this starting point, the connecting rods 12 move the carriage upwardly which gives the drill a powerful throw upwardly, which together with the force of the expanding buffer spring 27 acting on the grip 24, causes the drill to travel at a faster speed than that of the carriage 11 and hence it is caught by the engagement of the grip 24 with the propelling spring 26. The engagement of the grip 24 with the propelling spring 26 compresses said spring, places the same under tension and at the same time said spring absorbs the force of the projected drill and stops the same for reverse projecting movement.

The carriage 11, during its downward movement by the connecting rod 12, gives the drill a powerful downward thrust that is accelerated by the force of the expanding propelling spring 26 which causes the drill to attain a high velocity. During the downward thrust of the drill, the grip 24 first engages the buffer spring 27, compresses the same and then engages the striker plate 25 and is stopped thereby, and as the drill advances into the material being drilled, the momentum thereof causes said drill to slip in or feed through the striker plate 25.

The process of rotating the drill is as follows, to-wit: during the upward travel of the carriage 11 the link 22, acting on the crank arm 21, turns the sleeve bearing 20 to the left without rotating the drill, for the reason that the spring 26 is out of engagement with the grip 24 or in other words, the connection, to wit: the frictional engagement between the propelling spring 26 and the grip 24, is broken. When the carriage 11 has reached the limit of its upward travel, the momentum of the drill causes said drill to travel endwise relative to the carriage 11, which brings the grip into contact with the lower end of the spring 26 so that by the time the drill reaches the limit of its upward travel, said spring has been compressed to such an extent as to cause sufficient friction between the grip 24 and the inner end of the spring 26 so as to cause the drill to be rotated by the spring 26 as the carriage 11 is travelling downwardly, as will now appear. Obviously, the grip 24 and the inner end of the spring 26 afford a friction clutch. During the downward travel of the carriage 11, the link 22 acting on the crank arm 21 turns the sleeve bearing 20 in the carriage 11 and hence turns the drill through the spring 26 and the grip 24. It will thus be seen that while the sleeve bearing 20 is given one complete oscillation during each cycle of operation of the drill, the action thereof is negative during the upward travel of the car-

riage 11 and positive during the downward travel thereof, so that the drill is given steps of rotary movement in a constant direction. The purpose of turning a drill during drilling operation is too well known to need any comment here.

The parts thus far described are fully described and broadly claimed in my patent heretofore identified except the hollow shaft 16, which takes the place of the shaft described in said patent, the adaptor and the coupling.

Referring now in detail to the invention, the adaptor 18 has an axial passageway 28, the upper end of which is in communication with the interior of the hollow shaft 17. At the lower end 15 of the passageway 28 is a valve seat 29 and formed in said shaft below the valve seat 29 is an intake chamber 30. A port 31 extends through the valve seat 29 and connects the chamber 30 to the passageway 28. Normally, the port 31 is closed by a check valve 32, in the form of a ball, which rests on the valve seat 29. Diametrically opposite pairs of intake ports 33 lead from the exterior of the adaptor 18 to the chamber 30. These ports 33, as shown, are upwardly and inwardly inclined.

A hose connector 34, in the form of a short upright pipe, is detachably secured at its lower end to the upper end of the shaft 16 by a coupling 35 that is identical with the coupling 17. One end of a hose 36 is telescoped over the upper end portion of the connector 34 and secured thereto by a clamp 37. The hose 36 is carried by a plurality of sleeve-like members 38 and extends longitudinally over the upper edge of a horizontally disposed arm 39 cut from a wooden board and positioned edgewise in a vertical plane. This arm 39 is attached at one end to the hose connector 34 by a hinge 40 for oscillatory movement in a vertical plane, and is held suspended at its other end by a rope 41 from the upper end of a mast 42. This mast 42 is supported from the tilting frame 10 in an upwardly and outwardly inclined position relative to the shaft 16 by upper and lower crosstie members 43. The rope 41 is intermediately held by a guide tube 44 through which tube the rope 41 is free to slide endwise. Said rope 41 is secured at one end to the outer end of the arm 39 by an eye 45 and the other end portion of the rope 41 is secured to the mast 42 by a cleat 46. The tube 44 is in the form of an inverted U with one of its legs rigidly secured to the mast 42 and with its other leg arranged to hold the respective end portion of the rope 41 in a position in which the arm 39 is laterally spaced from the mast 42. Said tube 44 at its ends are outwardly flared so that the rope 41 will slide therethrough without undue wear.

Each sleeve-like member 38 has a flange 47 that overlaps the arm 39, is bolted thereto and rigidly secures the respective member 38 to said arm. The internal diameter of the member 38 is somewhat larger than the external diameter of the hose 37 so that said hose will freely turn therein, as will presently appear.

The hinge 40 includes a pair of hinge straps 48 between which the inner end portion of the arm 39 extends, and said straps are bolted to the arm 39. These straps 48 project outwardly of the respective end of the arm 39, embrace the upper end portions of a pair of upright straps 49 and are pivoted thereto, as indicated at 50.

The hinge straps 49 are rigidly secured at their lower end portions to a sleeve-like metallic member 51 at diametrically opposite points. The hose

connector 35 extends axially through the member 51. A relatively soft rubber sleeve 52 is interposed between the connector 35 and the sleeve 51 and connects the hinge 40 indirectly to the shaft 16. The purpose of the rubber sleeve 51 is to form a cushion between the drill and the arm 39. The sleeve 52 is held against endwise movement in the member 51 by the contracted upper end portion of said member and a washer 53 secured to the connector 35 at the bottom of said sleeve. The hinge straps 49 are connected near their upper ends by a cross-tie member 54 that is outwardly bowed to afford clearance for the hinge straps 48. The hose 36 extends midway between the hinge straps 48 and 49 and a stop shoulder 55 on said hose, near its outer end portion engages the outer end of one of the members 38 and holds the hose 36 against endwise movement toward the hose connector 35.

The hose 36 at its free end portion is telescoped into the inner end portion of a metal conduit 56 that lies longitudinally on the upper edge of the arm 39 at its outer end portion. Flanges 57 on the conduit 56 overlap the arm 39 and are bolted thereto. One end of a long hose 58 that reaches nearly to the ground is telescoped onto the outer end of the conduit 56 and is secured thereto by a clamp 59. The end portions of the members 38 and the inner end of the conduit are outwardly flared to prevent undue wear on the hose 36.

Operation

The process of taking samples of the earth by means of the apparatus embodied in a drilling machine as above described may be briefly stated as follows: The bit 19 cuts a hole, the diameter of which is considerably larger than the diameter of the shaft 16 so that there is considerable clearance between the wall of the drilled hole and the shaft of the drill. Water is either poured down the drilled hole or a water pipe, not shown, may be lowered into said hole with its discharge end above the bit 19. Sufficient water is kept in the drilled hole which when mixed with the material or materials cut by the bit 19 in drilling the hole, produces a slush. This slush enters the chamber 30 through the ports 33 and when the valve ball 32 is open, enters the hollow shaft 16 through the port 31. During the violent upward stroke of the drill, the column of slush is thrown upward therein and as the lower end of said column moves away from the valve seat 31, sufficient suction is produced by the moving column of slush to open the valve ball 31 and draw slush through the ports 33, chamber 30, port 31 and into the hollow shaft 16. From the hollow shaft 16, the slush therein is moved upward through the coupling 35, hose connection 34 and from thence horizontally through the hose 36 and the conduit 56. From the conduit 56, the slush flows downwardly in the hose 58 and the pull of the slush therein assists in lifting the slush in the hollow shaft 16. From time to time, for instance at intervals of a given number of feet, the hole is drilled and a sample of the material through which the bit is passing may be deposited from the hose 58 in a receptacle, as shown, a pail x.

During the turning of the drill about its axis, the hose 37 also turns therewith about its axis in the members 38 and the conduit 56. Obviously, the rope connection 41 permits free oscillatory movement of the arm 39 in a vertical plane, imparted thereto by the reciprocating movement of the drill. As the drill moves downwardly in the hole being drilled or when a section is added to

the shaft 16, the rope 41 may be adjusted to keep the arm 39 in substantially a horizontal position. In a broad sense, the adaptor 18 forms a part of the shaft 16.

5 The drawing illustrates a commercial form of the invention, but it will be understood that the same is capable of certain modifications as to details of construction, arrangement and combination of parts within the scope of the invention herein disclosed.

10 What I claim is:

1. In a drilling machine, a hollow shaft having on its lower end a bit, means for reciprocating the shaft, a port leading from the exterior of the shaft to the interior thereof, a check valve normally closing the port, means for rotating the shaft, a non-rotatable conduit, a hose attached at one end to the upper end of the shaft for rotation therewith and leading laterally therefrom with its outer end portion loosely extending into the conduit, and means supporting the hose with freedom for rotation with the shaft and in the conduit.

20 2. In a drilling machine, a hollow shaft, means for reciprocating the shaft, a port leading from the exterior of the shaft to the interior thereof, a valve normally closing the port, means for rotating the shaft, a horizontally disposed arm hinged at one end to the upper end of the shaft for oscillatory movement in a vertical plane, means supporting the arm at its other end for raising or lowering movement, a conduit on the arm, and a hose carried by the arm and attached at one end to the upper end of the shaft for rotation therewith and leading laterally therefrom with its outer end portion loosely extending into the conduit.

30 3. In a drilling machine, a hollow shaft, means for reciprocating the shaft, a port leading from the exterior of the shaft to the interior thereof, a valve normally closing the port, means for rotating the shaft, a horizontally disposed arm hinged at one end to the upper end of the shaft for oscillatory movement in a vertical plane, means supporting the arm at its other end for raising or lowering movement, a conduit on the arm, a hose carried by the arm and attached at one end to the upper end of the shaft for rotation therewith and leading laterally therefrom with its outer end portion loosely extending into the conduit, and a second hose leading from the conduit.

40 4. In a drilling machine, a hollow shaft, means for reciprocating the shaft, a port leading from the exterior of the shaft to the interior thereof, a valve normally closing the port, means for rotating the shaft, a horizontally disposed arm hinged at one end to the upper end of the shaft for oscillatory movement in a vertical plane, means supporting the arm at its other end for raising or lowering movement, a conduit on the arm, a hose carried by the arm and attached at one end to the upper end of the shaft for rotation therewith and leading laterally therefrom with its outer end portion loosely extending into the conduit, and a cushion in the hinge connection between the arm and the shaft.

5. In a drilling machine, a hollow shaft, means for reciprocating the shaft, a port leading from the exterior of the shaft to the interior thereof, a valve normally closing the port, means for rotating the shaft, a horizontally disposed arm hinged at one end to the shaft for oscillatory movement in a vertical plane, a mast on the drilling machine, a cable intermediately supported from

the mast and having one of its ends attached to the other end of the arm, means for adjustably securing the other end portion of the cable, a conduit on the arm, and a hose carried by the arm and attached at one end to the upper end of the shaft for rotation therewith and leading laterally therefrom with its outer end portion loosely extending into the conduit.

6. In a drilling machine, a hollow shaft, means for reciprocating the shaft, a port leading from the exterior of the shaft to the interior thereof, a valve normally closing the port, means for rotating the shaft, a horizontally disposed arm hinged at one end to the upper end of the shaft for oscillatory movement in a vertical plane, means supporting the arm at its other end for raising or lowering movement, a conduit on the arm, horizontally spaced tubular guides on the arm, and a hose attached at one end to the upper end of the shaft for rotation therewith, said hose extending loosely through said guides with its outer end portion loosely extending into the conduit, said hose being free for rotation in said guides and conduit.

7. In a drilling machine, a hollow shaft, means for reciprocating the shaft, a port leading from the exterior of the shaft to the interior thereof, a valve normally closing the port, means for rotating the shaft, a horizontally disposed arm, a hose connector forming an extension of the shaft at

its upper end, a hinge connecting the arm at one end to the hose connector for oscillatory movement in a vertical plane, means supporting the arm at its other end for raising or lowering movement, a conduit on the arm, and a hose carried by the arm and attached at one end to the hose connector for rotation with the shaft and leading laterally therefrom with its outer end portion loosely extending into the conduit, said hinge including a sleeve-like member through which the hose connector extends axially and a rubber sleeve interposed between the hose connector and said member and connecting said member to the hose connector.

8. In a drilling machine, a hollow shaft, means for reciprocating the shaft, a port leading from the exterior of the shaft to the interior thereof, a valve normally closing the port, means for rotating the shaft, a horizontally disposed arm hinged at one end to the shaft for oscillatory movement in a vertical plane, a mast on the drilling machine, a tubular cable guide in the form of an inverted U secured to the mast, a cable extending through said guide and having one of its ends attached to the other end of the arm, means for adjustably securing the other end portion of the cable, and hose carried by the arm and attached at one end to the upper end of the shaft for rotation therewith and leading laterally therefrom.

ALBERT HOSSFELD.
